CLAIM

The ornamental design for a self injection device window, as shown and described.

DESCRIPTION

FIG. 1 is a perspective view of an embodiment of a self injection device window showing our new design;

FIG. 2 is an enlarged perspective view of the self injection device window shown in FIG. 1;

FIG. 3 is a front elevational view of the self injection device window shown in FIG. 1;

FIG. 4 is a top view of the self injection device window shown in FIG. 1;

FIG. 5 is an enlarged top view of the self injection device window shown in FIG. 4;

FIG. 6 is a left side elevational view of the self injection device window shown in FIG. 1;

FIG. 7 is a right side elevational view of the self injection device window shown in FIG. 1;

FIG. 8 is a bottom view of the self injection device window shown in FIG. 1; and,

FIG. 9 is a rear elevational view of the self injection device window shown in FIG. 1.

Broken lines in the drawing figures represent unclaimed environmental structure, are for illustrative purposes only, and form no part of the claimed design.
